UNITED STATES PATENT OFFICE.

IRA W. NONNEMAN, OF WARREN, OHIO, ASSIGNOR TO THE BORDEN COMPANY, OF WARREN, OHIO, A CORPORATION OF OHIO.

PIPE-CUTTER.

1,394,781.

Specification of Letters Patent. Patented Oct. 25, 1921.

Application filed December 2, 1918. Serial No. 264,917.

To all whom it may concern:

Be it known that I, IRA W. NONNEMAN, a citizen of the United States, residing at Warren, in the county of Trumbull and 5 State of Ohio, have invented a certain new and useful Improvement in Pipe-Cutters, of which the following is a full, clear, and exact description, reference being had to the accompanying drawings.

10 This invention relates to pipe cutters of the type wherein the cutting members are carried by an annular rotary frame adapted to surround the pipe, and an oscillatory feeding device is provided to rotate the 15 frame step by step. The general object of the invention is to provide a cutting tool of this type which shall be simple, effective and durable. More specifically, among the 20 objects of the invention may be mentioned provision for readily disconnecting the frame to allow it to be passed laterally over an intermediate portion of a pipe; provision for effectively and quickly anchoring the pivot of the oscillating member to pipes of 25 various sizes, and provision for the quick and definite adjustment of the knives for the different sizes of pipe.

The invention is hereinafter more fully described in connection with an approved embodiment thereof shown in the drawings. 30 In these drawings, Figure 1 is a front elevation of the pipe cutter; Fig. 2 is a rear elevation thereof; Fig. 3 is a radial section through one of the knife housings showing 35 a knife in cutting engagement with a portion of pipe; Fig. 4 is a transverse section through one of the knife housings on the broken line 4-4 of Fig. 3, showing one of the frame sections, principally in plan; Fig. 40 5 is a detail of the block carrying the ratchet pawl for feeding the cutter; Fig. 6 is an edge view of the oscillatory feeding handle; Fig. 7 is a detail of the chain anchorages connected with the oscillatory lever; Fig. 8 45 is a radial section of the rotary frame.

Referring to the various parts by numerals, 10, 11, 12 and 13 indicate four sections of the annular rotary frame. Each of 50 these sections is correspondingly arcuate for a distance of ninety degrees so that when the four sections abut a complete annular ring is made. In use the four sections are rigidly connected together. The means shown for this purpose comprises links 20 55 extending across the meeting ends of three

of the sections and pivotally connected with them and a bolt 25 and nut 26 connecting together the other two meeting ends of the sections. The removal of the nut 26 enables the separations of the sections 10 and 13 and 60 the whole frame then becomes articulate and can then be swung open, enabling it to be passed across a pipe where it is impracticable to pass the tool over the end of the pipe.

65 Referring more specifically to the frame shown, each section comprises a cylindrically arcuate portion 15 having an edge flange 16 terminating at each end in eyes. All of these edges but one have their holes parallel with the cutter axis, as illustrated at 17. The remaining eye 18 has its hole tangential. The links 20 are arranged in pairs on opposite sides of these eyes 17 and are pivotally connected thereto by bolts 22 which 70 pass through the links and intermediate eye. The bolt 25 has a bifurcated end 27 which embraces the eye 17 on the section 13 and this bolt passes loosely through the eye 18 on the section 10. When the nut 26 is in 75 place and screwed up tight the four sections 80 tightly abut each other, and the frame operates as a rigid unit.

Centrally formed on each frame section is a radial boss 19 preferably integral with 85 the frame portions 15 and 16 and having a radial groove with undercut sides—these grooves providing ways for the cutter housings. The cutter housings are designated 90 30. They are box-like devices carrying the knives 40 by means hereinafter specifically described, and they have ribs 31 on their backs which slidably occupy the ways in the frame members. Each rib has a series of ratchet teeth 32 in its rear face, and coacting 95 with these teeth are pawls 50 mounted in recesses in the bosses 19 and pressed toward the housings by springs 51 secured to the rear face of the bosses.

The ratchet connection described enables 100 the housings to be readily adjusted for different sizes of pipe, it being only necessary to push the housings radially inward to adjust the cutter from the largest size of pipe to the smallest. In Figs. 1 and 2, A indicates 105 the outside diameter of the largest size of pipe and A' the outside diameter of the smallest size with which the particular tool shown cooperates. The ratchet adjustment described may readily have the teeth 32 so 110

spaced (for instance one-eighth of an inch apart) that the knives may be set for all standard sizes of pipes by simply pushing in the housings. To adjust the housings outwardly the spring 51 is pried back and the housing and its rib slid outwardly.

The knife housing 30 is a rectangular box-like structure having a rigid back plate 33 and rigid side walls 34, a removable outer end 10 36 and a removable front plate 37, the end and front plates being normally rigidly secured by screws. Within the housing is a block 45 somewhat shorter than the interior of the housing so that it is capable of radial 15 adjustment therein, but guided by the side walls and front and back of the housing. To the face of this block is secured the knife or cutter 40 by screws 41. The cutter is preferably of the type having a cutting edge 20 43 and an abutment shoulder 44 in advance of such edge engaging the pipe and limiting the cut. This cutter freely occupies an opening 38 in the housing cover plate.

Within the block 45 is a central radial recess 46 which is occupied by a compression spring 47 bearing at its opposite ends against the base of the recess and the end cover 36 of the housing. To retain the block within the cutter housing I provide the bolt 30 48 which extends within the bore 46 and screws into the base of the block and extends out through the end plate 36 of the housing. A nut 49 screwing onto this bolt is adapted to abut the end plate of the housing and 35 limit the inward movement of the knife block and knife and prevent the separation of the parts.

Each housing rib 31 is provided at its inner end with a narrow hardened steel block 40 39 seating in a notch in the rib and held in place by a screw. These blocks are adapted to engage the pipe and provide an effective 45 guide for the tool.

Referring to Figs. 2, 5, 6 and 7, 60 indicates the oscillatory lever for feeding the cutter frame. This lever is pivoted at 61 to a block 62 which has two pairs of ears 63 and 64. Pivotally connected with these two ears are blocks 65 and 66. The block 65 is bifurcated to provide an anchorage for a chain 70. The other end of the chain has connected to it a bolt 67, which passes through an eye 68 on the block 66 and receives a nut 69. By tightening this nut the chain anchored at 50 65 may be drawn snugly about a pipe and clamp the pivot block 62 thereto. For different size pipes it is only necessary to hang different links of the chain in the bifurcated anchor block 65.

60 The oscillatory lever 60 is located in position alongside of the rear face of the cutter frame. This lever has at its outer end a socket 75 into which an ordinary operating handle 76 may be screwed. The lever is connected by a link 73 with a pawl carrier 80

which carries a pawl 86 adapted to engage a ratchet wheel 90 rigid with the cutter frame. Accordingly the oscillation of the handle 76 may feed the pawl back and forth and thus give a ratchet feed to the cutter. 70 This feed is varied according to the power required by varying the position of the pivot 78 of the link in a slot 79 in the lever.

The ratchet wheel referred to is preferably an integral part of the cutter frame, 75 each section of which carries at its rear face an arcuate overhanging rib 90 having ratchet teeth 91 on its outer face, these ribs abutting to make a complete ratchet wheel when the frame sections are connected. On 80 the inner edge of each rib is an arcuate groove 93 which becomes a circular groove when the sections are connected. The pawl carrier 80 has a flat portion 81 lying alongside of the ratchet wheel, and a flange 82 85 extending within this ratchet wheel and forming a bearing for the carrier. A movable gib 83 is secured to this flange and occupies the groove 93, thus securing the pawl carrier in place while allowing the free circumferential movement concentric of the ratchet wheel. 90

Outside of the ratchet wheel the pawl carrier has formed on its side a tubular housing 85 which carries the pawl 86. This pawl is 95 pressed inwardly by a compression spring 87 surrounding the stem of the pawl and bearing against its head at one end, at its other end bearing against the bushing 88 screwed into the housing. The housing has an ear 89 100 with which the link 73 from the oscillating lever connects.

When the frame has been placed about the pipe, the sections being rigidly held by the tightened nut 26, and the pivot block for 105 the lever 60 being rigidly clamped to the pipe by tightening the nut 69 and the link 73 properly connected to the lever, and the housings pushed in until the knives abut the pipe, the device is ready for operation. The 110 oscillation of the handle 76 gradually feeds the frame around the springs feeding the cutters into the pipe as the cutting progresses.

It will be seen that my cutting tool is simple in construction, is readily separable, both as to the cutter frame and as to the anchorage for the oscillatory mechanism, so that it may be placed laterally on pipes, and is adjustable for different sizes of pipes simply by 115 pushing in the housings and placing a different link of the chain in its anchorage block. When connected, the adjustable step by step feeding mechanism gives the desired power for turning the frame, while the springs in 120 the housings automatically take care of the cutting feed.

Having thus described my invention what I claim is:—

1. The combination of a set of arcuate 130

sections all of them except the extreme sections hinged together to make an openable frame, means for removably securing the extreme sections together to make the frame continuously annular, radial guideways carried by the sections, housings having ribs occupying the guideways, ratchet teeth on said ribs, pawls therefor carried by the sections, slideable blocks in the housings, knives carried by said blocks, and springs pressing the blocks inwardly.

2. An articulated annular frame made up of a series of arcuate sections hinged together, means for securing the free ends of the extreme sections together, radial ways carried by the sections, housings having ribs extending outwardly from the back thereof and guided in said ways, ratchet teeth preventing the outward movement of the housings while allowing an inward movement, spring pressed blocks carried by the housings, and knives carried by the blocks.

3. In a pipe cutter, the combination of an articulated frame composed of arcuate sections hinged together, means for securing the ends of the extreme sections together to make an annular frame, each section carrying a segment of a ratchet wheel which becomes complete when the frame is annular, an arcually movable carrier having an adjustably mounted pawl adapted to coact with such ratchet wheel, whereby the length of feeding stroke may be varied without varying the motion of the lever, means for moving the carrier, and cutters carried by the frame.

4. The combination of a frame composed of a plurality of arcuate sections hinged together, means for securing together the free ends of the extreme sections, an arcuate rib carried by each section, said rib having ratchet teeth on its outer face and a groove on its inner face, a pawl carrier adapted to lie alongside of said ratchet rib, said carrier having a gib occupying the internal groove, a pawl mounted on said carrier and adapted to engage with the ratchet teeth, and means for reciprocating the carrier.

5. The combination with an annular frame, of knives carried thereby, an annular row of ratchet teeth carried by the frame, a pawl coacting with the ratchet teeth, an oscillating lever linked with said pawl, a block to which the inner end of the lever is pivoted, means for anchoring one end of a chain to said block, and means adjustably connecting the block with the other end of the chain for tightening the chain about the pipe.

6. The combination with an annular frame, of a knife carried thereby, mechanism for rotating the frame, a block to which a portion of said mechanism is pivoted, a bifurcated block connected to the pivot block mentioned, a block connected to the other side of said pivot block and having an eye, a chain adapted to be anchored in said bifurcated block and extend around the pipe, and a bolt secured to the other end of the chain and adapted to extend through said eye and provided with a nut pulling on the chain.

7. The combination with an articulated annular frame composed of sections hinged together (the free ends of the extreme sections being removably connected together), knives carried by different sections, an annular row of ratchet teeth carried by the frame and composed of ratchet ribs on the respective sections, a pawl carrier arcually slideable about said ribs, a pawl mounted in the carrier and adapted to coact with said ratchet teeth, an oscillating lever linked with said pawl carrier, a block to which the inner end of the lever is pivoted, a bifurcated block pivoted to the pivot block mentioned, a block pivoted to the other side of the pivot block and having an eye, a chain adapted to be anchored in said bifurcated block and extend around the pipe, and means extending through said eye and adapted to pull on the chain.

In testimony whereof, I hereunto affix my signature.

IRA W. NONNEMAN.
